SINK

Kay L. Ruggles, Salt Lake City, Utah, assignor, by mesne assignments, to American Standard Inc., New York, N.Y., a corporation of Delaware

Filed Sept. 6, 1966, Ser. No. 3,754

Term of patent 14 years

(Cl. D23—58)

FIGURE 1 is a perspective view of my new design for a sink;

FIGURE 2 is a plan view of the device shown in FIGURE 1;

FIGURE 3 is a side elevation of the device shown in FIGURES 1 and 2;

FIGURE 4 is an end elevation of the device shown in FIGURES 1 and 2; and

FIGURE 5 is a profile view of the interior of the bowl and of the sink top as viewed on the line V—V looking in the direction indicated by the arrows as shown in FIGURE 3.

The dominant features of my invention reside in the portions shown in full lines.

I claim:

The ornamental design for a sink, substantially as shown and described.
